UNITED STATES PATENT OFFICE.

ALBERT MAURER, OF BROOKLYN, AND FREDERICK J. VON KAENTZEL, OF NEW YORK, N. Y.

LATCH.

1,317,092.

Specification of Letters Patent. Patented Sept. 23, 1919.

Application filed April 23, 1919. Serial No. 292,037.

To all whom it may concern:

Be it known that we, ALBERT MAURER and FREDERICK J. VON KAENTZEL, citizens of the United States, and residents of the city of 5 New York, borough of Brooklyn, in the county of Kings and State of New York, and borough of Manhattan, in the county and State of New York, respectively, have invented a new and Improved Latch, of 10 which the following is a description.

Our invention relates to a latch or lock and more particularly to a latch or lock adapted for use on lockers, cupboards, and the like. The device is of the type in which 15 a casing adapted to be secured to the door has a manually slideable latch bolt adapted to engage in a keeper applied to the frame or jamb. The slide bolt and the relatively fixed keeper have members adapted to be 20 brought into register for receiving a padlock or the like for positively locking the door.

The invention has for its object to provide a latch or lock of the type indicated 25 and improved in various particulars with respect to simplicity and durability of the parts and with regard to the facility with which the lock may be manipulated either for relying on the latch bolt alone and its 30 engagement with the keeper or to bring the parts to positions for receiving the padlock.

Reference is to be had to the accompanying drawings forming a part of this specification, it being understood that the drawings 35 are merely illustrative of practical examples of the invention.

Figure 1 is a face view of a latch embodying our invention in one form;

Fig. 2 is a horizontal section on the line 40 2-2, Fig. 1;

Fig. 3 is a longitudinal section at right angles to Fig. 2 as indicated by the line 3-3, Fig. 2;

Fig. 4 is a cross section on the line 4-4, 45 Fig. 1;

Fig. 5 is a longitudinal section corresponding generally with Fig. 2 but illustrating another form of the invention in which the member on the bolt adapted to 50 receive a padlock is swingable on the bolt instead of being a rigid part thereof, the view showing the parts latched but not in position to receive a padlock;

Fig. 6 is a view similar to Fig. 5 but with 55 the swingable element of the latch bolt

brought into register with the fixed members on the keeper for receiving the padlock;

Fig. 7 is a horizontal section in a plane indicated by the line 7-7, Fig. 5;

Fig. 8 is a detail in cross section on the line 8-8, Fig. 6.

Referring first to the forms illustrated in Figs. 1 to 4, a suitable housing or casing 10 is adapted to be secured to a door A of a 60 cupboard, locker, or the like, there being indicated screws 11, Figs. 1 and 3, and the numeral 12 indicates a keeper adapted to be secured in fixed position on the jamb B by screws 13 or equivalent fastening means. 65 In the casing 10 is manually slideable a latch bolt 14 which has a forwardly projecting lug or ear 15 slideable with the sliding of the bolt in the slot 16 in the front of casing 10, said keeper having a registering slot 16^b for 70 receiving the locking ear 15. Obviously, a forward sliding of the bolt 14 to engage the keeper 12 will cause the door to be latched and by withdrawing the bolt from the keeper the door may be swung open. When 75 the bolt is in latching engagement with the keeper 12 the lug 14 is accommodated between and in register with relatively fixed locking ears 17 on the keeper 12, the element 15 having a hole 18 transversely 80 therethrough and the members 17 having registering holes 19 so that a padlock may be passed through the several elements 15, 17 to prevent withdrawal of the latch bolt and thereby positively locking the door. 85

The longitudinal movement of the bolt 14 in its casing 10 is limited by a pin 20 on the bolt and permitted limited movement in the slot 21, which preferably is in the back or inner side of the casing to be thus concealed. 90

In order to cause the latch bolt 14 to maintain its position when projected into the keeper or withdrawn into the casing 10, we provide a spring catch 22 in the form of a plate spring secured at one end as at 23 to the interior of the casing at a depression 24 therein, the depression permitting the spring to lie flush with the inner wall of the casing 10 to which the spring is secured. The free end of the spring has a stud or protuberance 105 25 which is adapted to be received in either of two notches 26, 27 in the bolt 14 to give sufficient holding action on the bolt to cause the latter to maintain its position unless positively moved. 110

In the form shown in Figs. 5 to 8, the casing 10^a is secured by screws 11^a or the like and similarly the keeper 12^a corresponding with the keeper 12, is secured by 5 screws 13^a or the like. The latch bolt 14, instead of having a rigid locking member 15, has a member 15^a swingable on the latch bolt 14^a, said member having a shank 15^b pivoted as at 15^c to said bolt. The member 10 15^a and its shank are accommodated in the slot 16^a corresponding with the slot 16. To use the device as a latch, the bolt 14^a is simply slid forwardly to the position shown in Fig. 5 and sufficiently entered in the 15 keeper 12^a to cause the door to be latched. In this position of the bolt and its locking member 15^a, the latter is not in register with the fixed locking ears 17^a on the keeper 12^a. When, however, it is desired to lock 20 the parts, the shank 15^b is swung on its pivot 15^c to clear the front of the keeper 12^a and the bolt 14^a is shot farther into the keeper as will be understood from a comparison of Figs. 5 and 6. Thus, the locking member 15^a is finally brought to registering 25 position with the keepers 17^a so that holes 18^a, 19^a therein may receive a padlock, the same as in the first described construction. In the forms shown in Figs. 5 to 8, the same 30 spring 22^a is employed corresponding with the spring 22 and secured as at 23^a at a depression 24^a in the casing 10^a. A protuberance 25^a on the latch spring 22^a is adapted to engage in either one of three 35 notches instead of in two as in the first instance. Thus, as best seen in Fig. 7 there are notches 26^a, 26^b to receive the protuberance 25^a for holding the latch in either of the positions indicated in Fig. 5 or Fig. 6, 40 and in addition there is a notch 27^a corresponding with the notch 27 for holding the latch bolt 14^a in the retracted position and prevent its accidental outward movement.

We would state in conclusion that while 45 the illustrated examples constitute practical

embodiments of our invention, we do not limit ourselves strictly to the mechanical details herein illustrated, since manifestly the same can be considerably varied without departure from the spirit of the invention 50 as defined in the appended claims.

Having thus described our invention, we claim as new, and desire to secure by Letters Patent:

1. A latch including a casing, a latch bolt 55 slidable therein, a keeper adapted to be secured to the door jamb in fixed position to receive said latch bolt, spaced locking ears in fixed position on said keeper and a locking ear on said latch bolt, said casing and 60 said keeper having registering slots accommodating the locking ear of the latch bolt in sliding movements of the latter, and the respective ears being adapted to be brought to register for receiving a padlock. 65

2. A latch of the class described including a casing, a latch bolt slidable therein, a keeper adapted to be secured to the door casing to receive the latch bolt, fixed locking ears on the keeper, and a fixed locking 70 ear on the latch bolt adapted to be accommodated between the first mentioned ears and in register therewith when the latch bolt is engaged with the keeper, whereby a 75 padlock may be engaged with the respective locking ears.

3. A latch of the class described including a casing adapted to be secured to the door, a latch bolt slidable therein, a keeper adapted to be secured in fixed position on the 80 door casing, to receive the latch bolt, a fixed locking member on said keeper, and a swingable locking member on said latch bolt, said swingable member and the latch being movable relatively to the keeper to bring the 85 swingable member into register with the fixed locking member of the keeper whereby said members jointly may receive a padlock.

ALBERT MAURER.

FREDERICK J. VON KAENTZEL.
